EGG YOLK SEPARATOR

Louis Magnesi, Walnut Creek, Calif.

Application January 24, 1949, Serial No. 433

Term of patent 14 years

(Cl. D44—29)

To all whom it may concern:

Be it known that I, Louis Magnesi, a citizen of the United States of America, residing at Walnut Creek, in the county of Contra Costa and State of California, have invented a new, original, and ornamental Design for Egg Yolk Separator, of which the following is a specification, reference being had to the accompanying drawing, constituting a part hereof.

Figure 1 is a top perspective view of an egg yolk separator, showing my new design;

Figure 2 is a bottom perspective view; and

Figure 3 is an exploded view in the position of Figure 1.

I claim:

The ornamental design for an egg yolk separator, substantially as shown and described.

LOUIS MAGNESI.
